MOTOR-DRIVEN SPRING-ADJUSTING DEVICE FOR VEHICLES

Friedrich K. H. Nallinger, Stuttgart, Germany, assignor to Daimler-Benz Aktiengesellschaft, Stuttgart-Uнтерtukheim, Germany

Application June 26, 1952, Serial No. 295,792

9 Claims. (Cl. 267—57)

This invention relates to motor-driven spring-adjusting means and, more particularly, to a device for altering the tension of a spring system for a road vehicle, especially an additional auxiliary spring system which, according to requirements, is alternately put in tension respectively cut in, or relieved of tension respectively cut out.

It is a principal object of the present invention to provide a spring-adjusting device of the type indicated which is simple in design and easy to operate.

It is another object of the invention to provide a spring-adjusting device of the type indicated which is driven by an electric motor and reliable under service conditions.

With these objects in view, the present invention comprises a change-over switch gear adapted to automatically switch or preselect the drive, on reaching one or the other end position, to an opposite direction of rotation, thereby securing the advantage that the drive will be positively prepared for the next switching operation and that faulty manipulation by the driver is rendered impossible. Switching over is preferably achieved by means of a limit switch simultaneously or approximately simultaneously with the stopping of the drive, and preferably by means of a toggle switch adapted for rapid switching into one or the other end position by the action of a spring.

Another feature of the present invention consists in a construction whereby the change-over switch connects alternately, preferably by means of relays, a circuit for switching the driving motor to forward direction of rotation, and a circuit for switching the motor to backward direction of rotation in a manner whereby the circuits will yet be disconnected by the simultaneously operated limit switch so long until the circuit will be closed again when the switch has been shifted to neutral position by means of end stops.

A further feature of the invention concerns the particularly advantageous construction of the toggle switch. Thus there is attained a switch simpler in design, cheaper to build and of a particularly compact and rugged structure requiring but little space.

Other objects, features and advantages of the present invention will appear or be pointed out as the specification proceeds.

The accompanying drawings illustrate the preferred manner of carrying out the invention. In the drawings:

Fig. 1 is a wiring diagram of the arrangement provided by the invention.

Fig. 2 is a front view of the toggle switch.

Fig. 3 is a front view of the toggle switch lever which actually closes the circuit.

Fig. 4 is a top plan view of the switch, showing some parts in section.

Figure 5 is a cross-sectional view of the switch taken along a line perpendicular to the axis of shaft 52 between plate 62 and slide 59, and

Figure 6 is a partial axial cross-sectional view taken along line 6—6 of Figure 4.

The numerals 10 and 11 in Fig. 1 represent torsional

2

rods, for example, auxiliary springs additional to the main spring system of a motor vehicle which are attached to arms 12 and 13 abutting against spindles 14 and 15. The spindles 14 and 15 are slidably, but non-rotatably guided in a casing 16, and threadably engage the interiorly threaded extended hub portions of a gear 19 by means of left-hand and right-hand threads 17 and 18 respectively so that on rotation of the gear 19 in one direction, the spindles 14 and 15 will be displaced outwardly, i. e., away from gear 19, and on rotation of the gear 19 in opposite direction, the spindles 14 and 15 will be displaced inwardly, i. e., toward gear 19. The gear 19 is in mesh with reduction gears 20 driven by an electric motor 21 diagrammatically indicated on the drawing. The foregoing arrangement is substantially as shown, described and claimed in the copending patent application, Serial Number 282,589, filed on April 16, 1952, now Patent No. 2,705,139, entitled, "Spring-Adjusting Means for Vehicles." The electric motor 21 is connected to a source of current 22 through switches 23 and 24 which will be closed by coils 25 and 26 as soon as the respective coil is supplied with electric current. Excitation of coil or winding 27 induces the motor 21 to rotate in forward direction of rotation and excitation of a similar coil or winding 28 to rotate in backward direction of rotation.

In addition, the spindle 15 is connected to a bar 29 which carries stops 30 and 31. A lever 32 which may be actuated manually, may be displaced to the left or right from its center position thereby establishing an electrical circuit between power supply 22 and coil 25 or 26 by closing contacts 33 or 34 respectively.

However, lever 32 may also be actuated automatically by stops 30 or 31, respectively when the spindles 14 and 15 reach either their innermost position whereby stop 30 will shift the lever 32 from its position in which it establishes a circuit with contact 34, or their outermost position whereby stop 31 will shift the lever 32 from its position in which it establishes a circuit with contact 33. The approximate position of the stop members 30 and 31 with the spindles 14 and 15 at their outermost end positions are indicated in dotted lines in Figure 1 and are designated 30' and 31', respectively.

The coils 25 and 26 are further connected with contacts 35 and 36 which may be alternately connected by means of the lever 38 of a toggle switch 38, 39 with the wire 37 leading to the ground. The toggle switch is actuated by stops, located on a gear 40 which will abuttingly engage the lever 39 and displace the same beyond the dead center position of a spring 41. As soon as the spring 41 has passed the dead center position of the levers 38, 39, the lever 38 of the toggle switch will be rapidly shifted from contact 35 to contact 36 or conversely. The gear 40 may be driven in any suitable manner as, for example, by a worm gear 42 from the motor 21 or by a gear member of the gearing 20, by way of example in such a way that it makes approximately half a revolution during the full travel of the spindles 14 and 15 from the no-load or partial load end-position to the full load end-position.

The method of operation of the spring-adjusting device according to Fig. 1 is as follows: In the particular position shown on the drawings, the torsional springs 10 and 11 are adjusted to lowest tension. The lever 32 is in the median or center position so that the circuit connecting the coils 25 and 26 and therewith the motor 21 is disconnected. If it is desired to activate or cut in the springs 10 and 11 respectively to adjust them to their greatest tension, the lever 32 will be shifted to the left whereby the contact 33 will be connected with the source of current 22. Since the toggle switch 38

is in abutting engagement with the contact 35, the current may flow through the coil 25. As a result of this, the switch 23 will be closed so that the coil 27 will now be supplied with current from the source 22 through 23 and the electric motor 21 will be driven in forward direction of rotation. The gear 19 is set in motion and the spindles 14 and 15 respectively are displaced outwardly so that the torsional springs 10 and 11 are put under tension.

As soon as the springs have attained their ultimate tension, the lever 32 will be engaged by the stop 31 and shifted to its median or center position where it is held, for example, by a detent. As a result thereof the switch 32 will be opened, the current flowing through the coil 25 and exciting coil 27 respectively will be interrupted and the motor 21 stopped. Previously to that the stop 49 on the gear 40 has already engaged the lever 39 and shifted it, with respect to the lever 38, into the dead center position. As soon as it passes the dead center position. As soon as it passes the dead center position, which takes place simultaneously with the shifting of the lever 32 into the median position, the lever 38, by the action of the spring 41, will also be shifted into its other end-position in that it now abuts against the contact 36.

Should it be desired now to inactivate or cut out the torsional springs 10 and 11 respectively to relieve them of the tension it is merely necessary to shift the lever 32 to the right so that the current will flow from the source of current 22 through the contact 34, coil 26, and contact 36 to the ground 37. As a result, the switch 24 will be closed, the exciting coil 28 supplied with current, whereby the electric motor 21 will be caused to run in backward direction of rotation. As soon as the end position is reached the lever 32 will be returned by the stop 30 to its median position, and the motor stopped. Simultaneously therewith the lever 39 will be returned and the lever 38 shifted into the position shown on the drawing.

Figures 2 through 6 show the constructional details of the toggle switch in accordance with the present invention referred to briefly in connection with the description of Figure 1, where the toggle switch was schematically indicated and designated by reference numerals 38 and 39.

The toggle switch rests in a housing, only a wall portion of which is shown in Figures 2, 5 and 6, where such wall portion is designated by reference numeral 57. The aforementioned gear 40 provided with stops 49 and 50 (Figures 2, 4 and 6) is mounted on a shaft 52 which extends up to the wall portion 57.

An intermediate plate 62 (Figures 2, 4 and 6), which is substantially parallel to the wall portion 57, is located between the gear 40 and the wall portion 57, and is fixedly connected with the latter by means of the brackets 64 (Figures 2, 4 and 5). A shaft 61 (Figures 2, 4, 5 and 6) is supported in the intermediate plate 62 above shaft 52 and parallel therewith. The lever 39 (Figures 2, 4 and 6) rests on shaft 61 and includes a central wedge-shaped extension 43 and wing-shaped stop or abutment members 47 and 48 (Figures 2 and 4). The stop or abutment members 47 and 48 extended outwardly from shaft 61, i. e., perpendicularly to the axial direction thereof, but are also displaced axially with respect to each other and thereby come to lie in the path of the stops 49 and 50 respectively of gear 40, which have different lengths, as best shown in Figure 4.

A slide member 46 (Figures 2, 4 and 6) is guided in its vertical movement by shafts 52 and 61 through appropriate slots or openings provided at both ends of the slide member 46, and is constantly urged upwardly by spring 45 which is fastened to the slide member 46 and to the intermediate plate 62. The slide member 46 carries a pin 44 which is directed toward the lever 39 and cooperates with the edges of the wedge-shaped extension 43.

5

The aforementioned parts cooperate in such a way that upon rotation of the gear 40 in direction of the arrow p' (Figure 2), the stop 49, after completing approximately one-quarter of a revolution, will abut against the projecting stop 47 of lever 39 and then attempts to swing the lever 39 in clockwise direction; the latter movement is, however, only possible when the pin 44 and slide member 46 are downwardly displaced by the wedge-shaped extension 43, against the action of the spring 45, to a point beyond the outer or lower extremity of the wedge-shaped extension 43. Continued application of the force by the wedge-shaped extension 43 against pin 44 will lower the pin 44 and slide member 46 against the spring pressure 45, and as soon as the pin 44 has reached the outer or lower extremity of the wedge-shaped extension 43, the lever 39 will be rapidly urged by the spring 45 into the other end position as at that point the lever 39 and therewith the wedge-shaped extension 43 may continue freely the clockwise rotation. In a corresponding manner the stop 50, on rotation of the gear 40 in direction of the arrow p , may be brought into abutting engagement with the stop 48 so as to swing the lever 39 in counterclockwise direction. As clearly shown in Fig. 4 stop or abutment members 47 and 48 at the lever 39 are also displaced with respect to each other in the axial direction of the shaft 61, so that stop 49 will come in contact with stop 47 only, and stop 50 with stop 48 only.

A further vertical slide member 59 (Figures 4, 5 and 6), which is also guided in its vertical movement by shafts 52 and 61 through appropriate slots or openings provided at both ends of the slide member 59, is located behind the intermediate plate 62. The further slide member 59 is constantly urged upwardly by spring 63, which is fastened to the further slide member 59 and to the intermediate plate 62. The slide member 59 further carries a pin 60 (Figures 2, 4, 5 and 6) on the side thereof turned away from the intermediate plate 62, i. e., on the side thereof directed toward the wall portion 57.

Another shaft 51 (Figures 3, 4 and 6) coaxial with shaft 61 is mounted in wall portion 57 on which is mounted the lever 38 (Figures 1, 2, 4, 5, and 6) between the further slide member 59 and the wall portion 57. The shaft 51 projects through the wall portion 57, and a switch lever 58 is mounted on the thus projecting part of shaft 51 on the other side of wall portion 57.

The lever 38 includes a wedge-shaped extension at one (lower) end thereof, the edges of which cooperate with the pin 60 of slide member 59 in the same manner as the edges of the wedge-shaped extension 43 of the lever 39 with the pin 44 of the slide member 46.

The lever 39 is fork-shaped at the other (upper) end thereof and is provided therewith with two spaced stop members 54 and 55 (Figures 2, 4 and 5) forming an opening therebetween.

The tongue 53 (Figures 2, 4, 5 and 6) which is provided at the upper end of lever 39 and which projects rearwardly, i. e., in the direction toward wall portion 57, in parallel relationship with shafts 51 and 61, extends into this opening between stop members 54 and 55 in such a manner as to cooperate with the one or the other stop member 54 or 55 to rotate the lever 38 in the one or other direction. Rotation of lever 38 produces corresponding rotation of shaft 51 and therewith rotation of switch lever 58 in the one or other direction.

As soon as the lever 38 is swung so much that the point of its wedge-shaped extension slides over the pin 60 against the force of the tension spring 63, the lever 38 will be rapidly urged by the spring 63 to continue its movement so as to rotate shaft 51, until the switch lever 58 connected with the lever 38 reaches one of its end positions where it contacts the point 35 or 36 elastically. This contact continues until the tongue 53 of the lever 39 contacts the opposite stop of the lever 38 and forces the wedge-shaped point of the lever over

70

75

the pin 60 of the slide 59 against the resistance of the spring 63. After the pin 60 has passed the wedge-shaped point of the lever 38, this lever 38 snaps toward the other side and establishes the next contact by means of the switch lever 58. Owing to this jerky snapping there occurs no sparking at the contacts.

The levers 38 and 39 as well as the slides 46 and 59 are formed from sheet metal stamping, the stops 47, 48, 53, 54, 55 being produced by punching or bending. By mounting the levers and the slides closely side by side on the shafts 61 and 51 a short overall length of the switch is obtained.

As to the operation of the toggle switch in connection with the overall system, reference should be made to the foregoing description of Figure 1.

What I claim is:

1. A device for adjusting a spring system of a vehicle comprising a spring-adjusting member alternately movable from one end position to another for bracing a vehicle spring, an auxiliary motor, means for transmitting the motion of said auxiliary motor to said spring-adjusting member, means for initiating movement of said spring adjusting member and limit switch means for automatically interrupting the movement of said spring-adjusting member upon arrival of said spring-adjusting member at one of said end positions, and means for automatically preselecting the reversal of the rotation of said auxiliary motor, said preselecting means comprising a limitedly shiftable switch member having a center position between two contact positions, two contact members alternately in contact with said switch member upon displacement of said switch member to one or the other contact positions thereof, at least one resilient member co-operating with said switch member for non-positively moving said switch member into one or the other contact position to thereby cause said switch member to snap into the contact position after passing the said center position, and stop members moving with said transmitting means for shifting during movement thereof, said switch member into one or the other position past said center position.

2. A device for adjusting a spring system of a vehicle comprising a spring-adjusting member alternately movable from one end position to another for bracing a vehicle spring, an auxiliary motor, means for transmitting the motion of said auxiliary motor to said spring-adjusting member, and means for automatically preselecting reversal of the rotation of said auxiliary motor, said preselecting means comprising a limitedly shiftable switch member having a center position between two contact positions, two contact members alternately in contact with said switch member upon displacement by said switch member to the one or other contact positions, at least one resilient member co-operating with said switch member to snap said switch member into contact position after passing said center position, and stop members moving with said transmitting means for shifting during movement thereof said switch member into one or the other position past said center position.

3. The device as claimed in claim 2, wherein said means for automatically preselecting reversal further comprises a limitedly revolvable lever having a center position for moving said switch member, a rotatable disk carrying said stop members and in driven connection with said transmitting means, counter-stops on said lever co-operating with said stop members in such a way, that they will be carried along by said stop members to thereby swing said lever from one to the other end position.

4. The device as claimed in claim 2, wherein said stop members are located in different planes of motion, and wherein said means for automatically preselecting reversal further comprises a limitedly revolvable lever provided with counter-stop members likewise located in different planes of motion, said counter-stop members

and said stop members being so arranged with respect to each other that the plane of motion of one of said stop members will be in register with the plane of motion of one of said counter-stop members so that each stop member will come in contact with only one of said counter-stop members.

5. A device for adjusting a spring system of a vehicle comprising a spring-adjusting member for bracing a vehicle spring and alternately movable from one end position to the other, an auxiliary motor, means for transmitting the motion of said auxiliary motor to said spring-adjusting member, manual switch means for starting and stopping said auxiliary motor operative to energize said auxiliary motor upon closure thereof to rotate in only one predetermined direction of rotation, limit means for automatically operating said switch means when said spring-adjusting member has reached one or the other end position, and means allowing actuation of said motor only in one direction from a given position and for automatically preselecting the reversal of the direction of rotation of said auxiliary motor to enable subsequent rotation thereof only in the opposite direction of rotation from the prevailing direction of rotation, said limit means including means for actuating the preselecting means in response to the motion of said spring-adjusting member.

6. A device for adjusting a spring system of a vehicle comprising a spring-adjusting member, an electric motor, manual switch means for energizing and de-energizing said motor, a gearing between said electric motor and said spring-adjusting member, means operatively connected with said spring-adjusting member and said gearing allowing actuation of said motor only in one direction from a given position and for automatically preselecting the reversal of the direction of rotation of said electric motor only upon completion of the movement of said spring-adjusting member including means for actuating said preselecting means by said gearing, and two stop members moving with said spring-adjusting member and cooperating with said switch means in response to travel by said spring-adjusting member to a predetermined position only to shift said switching means by one of said stop members whereby the excitation for said electric motor is cut out and preselection for operation in the opposite direction during the next energization is obtained.

7. A device for adjusting a spring system of a vehicle comprising spring-adjusting means alternately movable from one end position to another, driving means connected to said spring-adjusting means and adapted to alternately drive said spring-adjusting means into opposite directions, control means for initiating movement of said driving means and including means for automatically stopping said driving means upon arrival of said spring-adjusting member at one of said end positions, and further means allowing actuating of said driving means only in one direction from a given position and operative only upon arrival of said spring-adjusting member at one of said end positions for preconditioning said driving means to enable reversal of said driving means and thereby drive said spring-adjusting member thereupon only in the opposite direction during the succeeding engagement thereof until arrival of said spring-adjusting member at the other end position.

8. A device for adjusting a spring system of a vehicle comprising spring-adjusting means alternately movable from one end position to another, driving means connected to said spring-adjusting means for alternately driving said spring-adjusting means in either one of the two opposite directions until said spring-adjusting means reaches one of said end positions, means for starting said driving means including means for automatically stopping said driving means upon arrival of said spring-adjusting means at one of said end positions, and further means allowing movement of said driving means in only

one direction from a given position and operative upon arrival of said spring-adjusting member at one of said end positions to precondition said driving means to drive said spring-adjusting member only in the opposite direction during the succeeding engagement of said driving means until said spring-adjusting means reaches the other end position.

9. The device claimed in claim 5, wherein said auxiliary motor is a reversible electric motor.
